UNITED STATES PATENT OFFICE.

JOHN A. RYAN, OF HOT SPRINGS, SOUTH DAKOTA, ASSIGNOR OF ONE-HALF TO JAMES W. ALDRIDGE, OF HOT SPRINGS, SOUTH DAKOTA.

RATTLE.

1,158,298.

Specification of Letters Patent. Patented Oct. 26, 1915.

Application filed July 16, 1915. Serial No. 40,294.

To all whom it may concern:

Be it known that I, JOHN A. RYAN, a citizen of the United States, residing at Hot Springs, in the county of Fall River and 5 State of South Dakota, have invented certain new and useful Improvements in Rattles; and I do hereby declare the following to be a full, clear, and exact description of the invention, such as will enable others 10 skilled in the art to which it appertains to make and use the same.

This invention relates to new and useful improvements in rattles and more particularly to that type of rattle used for the 15 purpose of amusement, of infants.

Another object of this invention is to provide a rattle of novel construction, which is particularly attractive to the eye and which cannot be disassembled without breaking.

20 A further object of the invention is to provide a rattle having a plurality of cells in which the loose members or balls are retained.

Still another object of the invention is to 25 provide a rattle having a number of exposed faces which will materially increase the sound produced thereby.

With these and other objects in view, the 30 invention consists in the novel combination and arrangement of parts which will be fully set forth in the following specification and accompanying drawings, in which:—

Figure 1 is a side view in elevation of a 35 rattle constructed in accordance with this invention showing the handle portion partially broken away. Fig. 2 is a view similar to Fig. 1 from another side thereof. Fig. 3 is a top plan view of Fig. 1. Fig. 4 is a sectional view on line 4—4 of Fig. 1. Fig. 5 is 40 a sectional view on line 5—5 of Fig. 1. Fig. 6 is a sectional view on line 6—6 of Fig. 2. Fig. 7 is a detail perspective view of one of the elements making up the rattle, and Fig. 45 8 is a fragmentary perspective view of the upper end of the handle.

Referring now to the drawings by characters of reference, the numeral 1 designates as an entirety, the handle provided with the gripping portion 2 having formed at its upper end, the reduced neck 3. This neck connects the rectangular portion 4 with the gripping portion 2 and the rectangular portion terminates at its upper end in the knob 5. Formed centrally of the rectangular

member 4 and extending from one face 55 thereof is a suitable transversely extending flange 6, which acts as a retaining flange to hold the handle in the head of the rattle.

The rattle is formed of a plurality of elements best illustrated in Fig. 7, which are 60 designated generally by the numeral 7 and each of these elements comprises a body 8 having rounded ends 9. Formed at each end of the body 8 are the upstanding portions 10 and formed intermediate the ends of the 65 body is a transversely extending flange 11. Both the upstanding portions 10 and the flange 11 extends from one face of the body and when the various elements are assembled, the face from which these members 70 10 and 11 project is disposed inwardly.

In assembling the device, the strips are forced in place to form a plurality of cells or chambers 12 in which the balls or shot 13 is held. The strips are assembled so that 75 their smooth faces 14 are disposed outwardly and in such a way that the arcuate ends 9 project from the main body of the head of the rattle forming a plurality of semi-circular extensions giving the rattle an exceeding- 80 ily odd and attractive appearance.

In assembling the device, the several parts are forced into place and the handle placed so as to project from the center of the device. The balls are placed in position in their 85 various chambers and due to the fact that there are provided eight separate chambers, each having six faces, which will be seen that the balls placed within the chambers will provide forty-eight faces against which 90 they may be impinged, thereby increasing the sound made by the rattle, thus multiplying the effectiveness of the device.

While in the foregoing there has been 95 shown and described the preferred embodiment of this invention, it is to be understood that such changes may be made in the combination and arrangement of parts as will fall within the spirit and scope of the appended claims.

100 What is claimed is:—

1. A rattle comprising a head formed of a plurality of interlocking strips, said strips providing, when in their interlocked position a plurality of chambers, balls within 105 the chambers and a handle secured to the head and provided with a tongue engaging between two of the strips and thereby being

held against movement with relation to the head.

2. A rattle of the character described comprising a head formed of a plurality of interlocking strips, the whole forming a cube in general appearance and chambers formed at each corner of the cube, the walls of the chambers forming sounding boards and means within the chambers to be impinged

against the walls when the rattle is shaken 10 to cause a sound.

In testimony whereof I affix my signature in presence of two witnesses.

JOHN A. RYAN.

Witnesses:

H. W. MORGAN,

ARTHUR J. MILFORD.
